CLAIM

The ornamental design for a display screen or portion thereof with a graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with a graphical user interface, showing the new design.

The broken line showing an electronic device is provided for the purpose of illustrating environmental structure. All other broken lines illustrate the display screen and elements of the graphical user interface. Any subject matter shown in broken lines form no part of the claimed design.
